Primary Examiner — Cynthia Ramirez*Assistant Examiner* — Laura H Yu(74) Attorney, Agent, or Firm — Sterne, Kessler, Goldstein & Fox P.L.L.C.(57) CLAIM

The ornamental design for a shoe, as shown and described.

DESCRIPTION

FIG. 1 is a top, front perspective view of a shoe showing my new design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the shoe that form no part of the claimed design.

1 Claim, 7 Drawing Sheets(56)
